WRAPPING PAPER CUTTER

Earl J. Parr, Wendell, Idaho

Application June 17, 1938, Serial No. 214,334

6 Claims. (Cl. 164—84.5)

This invention relates to improvements in wrapping paper cutters, and it is particularly adapted for use in conjunction with wrapping paper wound on rolls.

It is common practice to provide for the mounting of single rolls of wrapping paper and to combine a cutter with a holder of the type in mind, said cutter comprising a pivoted blade which bears down upon the leading end of the paper. Inasmuch as paper rolls are quite bulky even in the smaller sizes, it is impracticable to use a holder of the foregoing type for more than one roll of wrapping paper. Consequently, when a plurality of rolls of as many widths of paper are intended to be made accessible to the clerk, the convenience thus afforded is offset by the waste of space that must accompany the distribution of the various rolls and their holders.

Another and perhaps more serious fault of the type of holder and cutter mentioned above is that in many instances the paper slips back past the cutter blade, making it necessary for the clerk to raise the blade and feed the leading end sufficiently far forward to restore the paper to its proper relationship to the cutter. The objections noted above, mainly those that concern the cutting or tearing of the paper, are avoided by the improved paper cutter, the objects of which are as follows:

First, to provide a paper cutter which is so arranged as to accommodate the leading ends of a plurality of rolls of wrapping paper, said cutter being so constructed that the leading ends of all of the rolls are brought fairly close together, thus constituting the cutter the focal point, so to speak, of all of the rolls.

Second, to provide a cutter for wrapping paper wound in rolls, the arrangement being such that said cutter is readily mounted either on top of or beneath a counter, provision being made to enable easy access to the leading edges of sheets of various sizes.

Third, to provide an offset in the spacer frame providing a finger space in which a person may insert a finger to start the paper.

Fourth, to provide for the tensioning of the movable jaw or floor so that it exerts a proper pressure upon the paper, a portion of said tensioning means serving as a guide for the paper.

Other objects and advantages will appear in the following specification, reference being had to the accompanying drawing, in which:

Figure 1 is a perspective view of the improved wrapping paper cutter illustrating the mounting of the cutter unit beneath a store counter.

Figure 2 is a perspective view of the cutter

unit, the movable member being shown partly lowered.

Figure 3 is a longitudinal section taken on the line 3—3 of Fig. 1.

Figure 4 is a cross section taken on the line 4—4 of Fig. 1.

Figure 5 is a perspective view of a modified type of paper cutter such as is adapted to be mounted in a drawer or cabinet.

Figure 6 is a cross section taken on the line 6—6 of Fig. 5, but also illustrating the association of the cutter with a drawer and paper roll.

It is desired to explain at the beginning that the term "cutter" is mainly an expression of convenience. The device is not an actual cutter in the sense of its having blades which produce a shearing action, but it does have edges across which the paper is torn so it will be understood that the quoted term refers to a cutter of this type.

The cutter unit is generally designated 1 in Figs. 1 to 4. This unit may comprise one or more individual cutters. The instant showing in Fig. 1 is of two cutters 2, 3 and a cover 4. These members are hingedly connected to compose a cutter bank, or cutter unit, as it has been called.

The foregoing unit is mounted in any desired location, but it is particularly adapted to be mounted beneath a store counter 5. The manner of mounting is described later in the sequence of description, attention being first directed to the cutter 3. This cutter has a floor 6 (Fig. 2) and an apron 7. These parts are in the angled relationship shown. The floor 6 has a hinge knuckle 8 on one end. The matching knuckles 9 (Fig. 1) of the cover member 4 are interfitting with the knuckle 8 and a pin 11 (Fig. 3) completes the hinge. There is an opening 12 in the floor 6 near the forward tearing edge 13. Said opening is spaced back from said edge, leaving a bridge 14 which maintains the continuity of the tearing edge. The cover member 4 has a recess 15 on its forward edge. This recess registers with the opening 12 when the cover is closed.

The apron 7 has an offset 16 on front. This offset comprises the lateral and back walls 17, 18, and merely consists of a continuation of the apron 7, formed inwardly in the particular locality of the opening 12, so as to provide a fairly large finger space 19 into which the clerk may insert his finger in order to touch the paper P (Fig. 4) through the bottom of the opening 12, said paper lying between the floor 6 and cover member 4 immediately above the recess 15. At the same time the clerk will press on top of the

paper through the opening 12 with his thumb, and thus secure a firm hold on the leading end of the paper, enabling him to pull it forward as far as desired prior to tearing it off across the 5 edge 13.

The floor 6 and its apron 7, together with the related parts, constitutes a frame. A function of said frame, other than its supplying the tearing edge 13, is to space the various cutters from 10 each other. Screws 20 (Fig. 3) comprise gauge means to both regulate the vertical spacing between the cover member 4 and the respective frame and to determine the width of paper to be dispensed by that particular cutter frame. The 15 screws are driven through threaded holes 21 in the floor 6. The screws are readily adjustable from above. Each one terminates in a stud 22, and inasmuch as the stud is of reduced size there is a resulting shoulder 23, which affords a 20 rest for the cover member 4 when the holes 24 in the latter are fitted upon the studs 22 in the closed position (Fig. 3).

The depth to which the screws are adjusted toward the floor 6 determines the vertical space 25 for the paper P. If it is desired to increase or diminish the space it is only necessary to adjust the screws 20 accordingly. Since the shouldered ends of the screws project into the space between the floor 6 and cover member 4, it follows that 30 they provide side guides for the paper P and at the same time determine the width of paper that can be directed through.

Said screws also perform a function in the tensioning of the cover member 4. A latch 25 35 slidably held by a guide 26, is drawn upon by a suitably anchored and connected spring 27. The head 28 of the latch is bent over into cam form at 29. This cam is so related to the free end of the cover 4 that when the cover is closed the latch 40 will not only serve to hold it in place, but will transfer the tension of the spring 27 to the cover by the cam action of the head upon the free end. Inasmuch as the cam action will vary in its 45 effectiveness dependent upon the altitude of the shoulders 23, it is readily seen that the foregoing adjustment of the screws 20 plays a part in the regulation of the tension upon the cover member 10.

The foregoing explanation would conclude the 50 description of the cutter 3 if the cutter unit were confined only to the one element. But it is proposed to provide a plurality of cutters, and to connect them so that each one can be swung enough to enable the insertion of the leading 55 ends of the different paper rolls. With this in mind, the cutter 3 includes a member 30 which, in a sense, serves as a top. Said member is parallel to the floor 6, giving the cutter 3 and every other cutter like it, a cross sectional U-shape 60 (Fig. 4). Said member 30 performs the precise function in respect to the cutter 2 as does the cover member 4 in respect to the cutter 3. Accordingly, the member 30 is hinged at 31 to the bottom of the cutter 2 and is also recessed at its 65 forward edge to register with an opening in said bottom.

In order to maintain the identity of corresponding parts in the cutter 2, they are designated by similar numbers, being distinguished only by 70 the addition of exponent letters a. Consequently, the foregoing bottom of the cutter 2 is designated 6a, the opening 12a and the recess 15a. The second latch is the same and is also distinguished from the other according to the foregoing plan.

75 The apron 7a of the cutter 2 has a plurality of

holes 32 through which screws or nails 32a (Fig. 4) are driven into any appropriate kind of a fixed support (Fig. 1) to firmly mount the cutter unit 1 beneath the counter 5. Thus the cutter 2 is made rigid. Both the cutter 3 and its cover 4 5 can be swung separately or together upon the respective hinges (arrows a and b, Fig. 2) the top member 30 of the cutter 3 acting in the capacity of a cover for the cutter 2 next highest.

The amount of swinging will be very slight; 10 only enough to enable directing the leading end of the paper roll through when making a start. The gauge screws 20, 20a of the cutters 3, 2 are at progressively less distances apart (Fig. 3), thus 15 accommodating sheets of successively smaller sizes. It is to be observed that the cutter 2 does not have a top equivalent to the member 30. Such a member is not necessary when there is no cutter above. If the cutter 3 were used singly, as suggested earlier in the description, its frame 20 would be precisely like the frame of the cutter 2, that is to say, without the top member 30. Then said cutter 2 would have a cover member like 4.

Reference is now made to Figs. 5 and 6. A 25 single cutter 33 is shown here. This is intended to have its support upon the front of a drawer 34 (Fig. 6). Said drawer has provision for mounting a roll of paper 35, and the leading end of the 30 paper P is brought forwardly through the cutter 33.

The latter comprises a floor 36 and apron 37 35 in angled relationship as before. But now the floor is projected to form a flange 38 which comprises the tearing edge and lies along the top of a slot 39 disposed horizontally of the drawer 34. This slot has an opening 40 which communicates with the finger space 41 of the cutter 33 and with the space beneath the floor 36. This enables the clerk to grip the leading edge of the paper from 40 above and below when the paper is cut flush with the tearing edge. Clips 42 now take the place of the hinge and spring latch of the cutter 2. These 45 clips secure a loose cover member 43 to the floor 36, the shouldered screws 44 being provided to variously space the cover member from the floor, assist in the tensioning of the cover member and to gauge the width of paper to be handled, precisely as before.

The floor 36 has an opening 45 and bridge 46. 50 The bridge is a continuation of the flange 38 and the tearing edge 47 is common to both. The cover member 43 has a matching recess 48, and the apron 37 has an offset 49 which provides the finger space 41, as before. Screws 50 (Fig. 6) are 55 driven through holes 51 in the apron 37 to secure the cutter 33 to the drawer 34.

From the foregoing description it is readily understood that a plurality of rolls of paper are intended to be mounted in bank form. These 60 rolls are of various widths designated by the leading ends in Fig. 1. These ends are brought forwardly through the cutters 2 and 3. When a sheet is torn off the tearing naturally is done close to the edge 13. It is not necessary to raise any 65 cover or cutter in order to start the sheet for the next tearing. This is done only when starting the paper through.

The clerk has only to insert a finger in the 70 space 19 so as to touch the paper on top and at the same time touch the paper from beneath with his thumb through the opening 12. This enables him to pull the paper forwardly with a center pull. His fingers will simply slip over the bridge 14 and when he has pulled the paper out far 75

enough he will tear it off in the manner already described. This operation is as true of the modification in Figs. 5 and 6 as it is of Fig. 1. The opening 40 (Fig. 6) which occurs above and below the slot 39 enables the clerk to have access to the finger space in the cutter 33.

I claim:

1. A wrapping paper cutter comprising a frame consisting of a floor and apron in angled relationship, said floor having an opening and the apron having an offset in communication with said opening so that the opening can be reached by inserting a finger in the offset, a cover member closely spaced from said floor and having a recess in one edge, connecting means movably joining the floor and cover member to maintain the recess in registration with said opening, and gauge means to both regulate the spacing between said cover member and floor and to determine the maximum width of paper insertible therebetween.

2. A wrapping paper cutter comprising a frame having a floor and apron, said floor having a flange providing a tearing edge, said apron being securable against a support, the flange being adapted to overlie one side of a slot in said support, an offset in the apron and a communicating opening in the floor providing a finger space accessible through the slot, a cover member which is recessed to match the opening, and clips to removably attach the cover member to said floor.

3. A cutter unit for use in conjunction with a plurality of rolls of wrapping paper of different widths, said unit comprising a plurality of frames one of said frames having a floor with an angularly disposed apron securable to a fixed support thus to firmly mount said unit contiguously to the paper rolls, a cover member having an apron and a floor in mutually angled relationship, a second cover member, said cover member being for the latter floor to complete a second frame, and the first-named cover member being for the former floor, the latter apron spacing the cover members and floors apart to lead the paper ends out from the rolls at different altitudes, and separate hinges connecting the cover members to the adjacent floors, enabling the optional swinging of the second cover member from its frame, and the swinging of said frame from the floor of the former frame, for the insertion of the respective paper roll ends, said floors and cover members having openings and the aprons having offsets all in registration

providing for the insertion of human fingers to grasp the paper ends.

4. A wrapping paper cutter comprising a frame adapted to be mounted contiguously to a roll of paper, said frame including a pair of members, at least one of said members providing a tearing edge, coupling means for coupling one end of the pair of members whereby said members are in connected relationship on opposite sides of the end of paper directed between said members from said roll, said members having registering openings enabling finger contact with opposite sides of the paper end at said openings, and means carried by one of the members, acting on the other member with a cam action to hold said other member under tension upon said paper end.

5. A wrapping paper cutter comprising a frame adapted to be mounted contiguously to a roll of paper, said frame including a pair of members, at least one of said members providing a tearing edge, coupling means for coupling one end of the pair of members whereby said members are in connected relationship on opposite sides of the end of paper directed between said members from said roll, said members having registering openings enabling finger contact with opposite sides of the paper end at said openings, means carried by one of the members, acting on the other member with a cam action to hold said other member under tension upon said paper end, and means fitted in one member having a stud of reduced size to fit a hole in the other member, said stud defining a shoulder on said means to engage said other member around the hole.

6. A cutter unit for use in conjunction with a plurality of rolls of wrapping paper of different widths, a plurality of floors, each floor providing a tearing edge for the respective end of a paper roll, upstanding aprons comprising parts of the floors, one of the aprons determining the vertical spacing of the floors and thereby determining the spacing of said paper ends, a cover closable into closely spaced relationship with each of the respective floors, one of the covers being part of said one apron, means connecting contiguous floors and covers and providing for the passage of said paper ends in the spaces between said floors and covers, and variously spaced gauge means extending between the respective floors and covers to match the width of the paper end positioned therebetween.

EARL J. PARR.
